[57] CLAIM

The ornamental design for a water fountain, as shown and described.

DESCRIPTION

FIG. 1 is a perspective view of a water fountain in accordance with the present design;

FIG. 2 is a front elevational view of said water fountain;

FIG. 3 is a top view of said water fountain;

FIG. 4 is a side elevational view of said water fountain, the side of the water fountain not shown being a mirror image of the side shown in this view; and,

FIG. 5 is a bottom view of said water fountain.
